UNITED STATES PATENT OFFICE.

DONALD BARNS MORISON, OF HARTLEPOOL, ENGLAND.

APPARATUS FOR DISCHARGING LIQUIDS FROM VESSELS.

1,232,370.

Specification of Letters Patent.

Patented July 3, 1917.

Application filed June 24, 1915. Serial No. 36,116.

To all whom it may concern:

Be it known that I, DONALD BARNS MORISON, a subject of the King of Great Britain and Ireland, residing at Hartlepool, in the 5 county of Durham, England, have invented Improvements in Apparatus for Discharging Liquids from Vessels, of which the following is a specification.

This invention relates to liquid discharging apparatus of the liquid seal type, and has reference to the discharge of liquids of different specific gravities from a closed vessel under a pressure which may vary between predetermined high and low limits. The 15 object of the invention is to provide apparatus whereby the liquids can at all times be reliably and automatically discharged from the vessel.

For this purpose there is placed between 20 the vessel and the liquid seal, a receiver which is of such capacity as will accommodate the liquid of least specific gravity and thus prevent its back flow into the vessel when the latter is working at a low pressure. The head of liquid in the receiver and 25 downward passage of the seal when under the low limit of pressure is sufficient to prevent back flow into the vessel, and the head of liquid in the upward passage of the seal 30 when under the high limit of pressure is sufficient to prevent vapor or gas from escaping from said vessel.

The invention is particularly applicable to steam regenerative accumulators in which 35 the heating medium is exhaust steam. In apparatus of this kind it has been usual to provide an oil separator in the pipe line through which exhaust steam is supplied to the accumulator, with the result that the 40 separator not only sets up a prejudicial back pressure but requires to be frequently cleaned. Now I have ascertained from careful tests, that irrespective of the fact that an oil separator may be used, the oil always 45 enters the accumulator with the steam through the water circulating and condensing devices, and when separated from the steam it mostly floats on the surface of the water in the form of scum, and if the scum 50 is carried by a surface flow to the place of discharge, as for example in the manner described in the specification of Letters Patent No. 1,081,132 of 1913, and then passes, in accordance with my present invention, 55 through an opening or over a weir into a receiver from which it is automatically dis-

charged, the effect is such that the water in the accumulator is maintained in a state of cleanliness and efficient condensation of the oily steam and the instantaneous regeneration of pure steam is promoted, whereby a high efficiency is not only obtained in the regenerative accumulator, but also in the turbine and condenser into which the steam may flow.

The accompanying drawings illustrate particular forms of my invention applied to steam regenerative accumulators.

Figure 1 represents a sectional side elevation of a steam regenerative accumulator 70 fitted with apparatus constructed according to my invention, and Fig. 2 represents a plan view at the level of the liquid in the accumulator shown in Fig. 1.

Figs. 3 and 4 are similar views to Figs. 1 75 and 2 and show in part a modified construction of the apparatus illustrated in Figs. 1 and 2.

With reference to Figs. 1 and 2. The accumulator is of similar construction to 80 those illustrated in the specification of Letters Patent No. 1,081,132 of 1913, and is fitted with water circulating and condensing devices which produce a surface flow of water toward the end of the vessel at which 85 the liquid discharging apparatus is placed. The oil and other floating matter is carried by the surface flow into the space *r* formed between the plate *e* and the end *m* of the vessel *a*, and in accordance with my invention 90 a receiver *b*, which is of such capacity as will accommodate the oily scum, is placed in communication at its upper end with the vessel *a* at the normal liquid level therein so that the oily scum, or other floating matter, 95 after passing through the opening *c* falls by gravity into the receiver *b*. With the object of automatically maintaining in the vessel *a* a pressure or vacuum within a predetermined range, the lower end of the receiver 100 *b* is connected to the liquid sealed tube *d* that is arranged concentrically within the tube *f*, the latter having a discharge branch *h* which is so disposed relative to the opening *c*, that the normal liquid level in the receiver *b* is maintained below the normal 105 liquid level in the vessel *a*, the depth of the receiver *b* and the downward passage *d* being such as will accommodate the oily scum and prevent its back flow into the vessel *a* 110 when the latter is working at a low pressure, and reduce to a minimum the amount of

oily scum remaining in the system when under a high pressure, so that at no time can the liquid of least specific gravity flow back from the receiver into the vessel *a*. The 5 head of liquid in the upper passage *f* is such that when under a high pressure the escape of steam from the vessel through the seal is prevented.

In Figs. 3 and 4 a vessel *n* is placed between the plate *e* and the end *m* in order to provide weirs over which the floating matter passes into the vessel *n* which communicates with the receiver *b*. The liquid seal consists of a U-shaped tube *d*, the discharge end of 15 the tube being disposed at such a height as will maintain under normal conditions a liquid level in the receiving chamber *b* below the liquid level in the vessel *a* and vessel *n*.

20 The receiver may be provided with covers or doors suitable for cleaning purposes.

What I claim is:—

1. The combination with apparatus comprising a liquid sealed device consisting of 25 downward and upward passages for discharging liquids of different specific gravi-

ties from a vessel under pressure, of a receiver placed between said vessel and said liquid sealed device, such receiver being adapted to accommodate the liquid of least 30 specific gravity and prevent its back flow into the vessel when the latter is working at a low pressure.

2. Apparatus for discharging float oil and 35 water from a steam regenerative accumulator in which the pressure varies between limits above and below the atmosphere, comprising a receiver having its upper end placed in communication with said accumulator, and a liquid sealed device consisting 40 of downward and upward passages for the flow of oil and water from said receiver which is of such capacity as will accommodate the oily scum and prevent its back flow into the vessel when the latter is working 45 at a low pressure.

Signed at London, England, this tenth day of June, 1915.

DONALD BARNS MORISON.
